LATHER MIXER

Filed March 26, 1932

UNITED STATES PATENT OFFICE

MELVIN BOLSTAD, OF WORTHINGTON, MINNESOTA

LATHER MIXER

Application filed March 28, 1932. Serial No. 601,395.

This invention relates to improvements in mixing devices and pertains particularly to a device for mixing lather for shaving purposes.

5 The primary object of the present invention is to provide a device for quickly furnishing a suitable lather for use in shaving and at the same time making it possible for the user to provide himself with just the 10 right amount of lather for the shaving operation, thereby conserving the soap.

Another object of the invention is to provide a lather mixer which provides warm water for use in forming the lather so that 15 the lather will be suitably warmed when withdrawn.

A still further object of the invention is to provide a novel lather mixer having an electric motor operated brush which rotates 20 upon a soap body within a suitable receptacle, thus rapidly forming a heavy lather which is drawn off from the receptacle through a suitable discharge opening.

The invention will be best understood 25 from a consideration of the following detailed description taken in connection with the accompanying drawing forming part of this specification, with the understanding, however, that the invention is not confined to any strict conformity with the showing of the drawing but may be changed or modified so long as such changes or modifications mark no material departure from the salient features of the invention as expressed in the appended claims.

In the drawing:—

Figure 1 is a view partly in elevation and partly in vertical section through the preferred form of the lather mixer embodying 40 the present invention;

Figure 2 is a view partly in vertical section and partly in elevation of a modified form of mixer.

Referring now more particularly to the 45 drawing wherein like numerals of reference indicate corresponding parts throughout the several views, the numeral 1 indicates a vertically disposed cylindrical receptacle mounted upon a base 2 which has an up- 50 standing threaded flange upon the top there-

of as indicated at 3, which threads into the lower end or bottom of the receptacle to close the same.

The wall of the receptacle is provided at a suitable elevation with a lather draw-off 55 spout 4 which is closed at its outer end by a valve of any suitable character, the valve here shown comprising a sliding disk or plate 5 which is normally held in position across the mouth of the nozzle by a spring 6 mounted in a suitable holder into which the disk is pressed when the nozzle is open.

In the upper portion of the receptacle 1 are two spaced partitions 7 and 8 which form the chambers 9 and 10. The chamber 60 10 is lined with a suitable insulating material as indicated at 11 and within this chamber is mounted an electric resistance heating coil 12, the terminals of which are connected by suitable wires 13 with a cable 14 upon the outside of the receptacle, which cable has one end connected with a suitable plug 15 for coupling it with a source of electric current supply.

The upper chamber 9 of the receptacle is 65 provided to contain water and this is discharged into the lower part of the receptacle or chamber 16 in which the lather is formed, through a tube 17 which leads from the wall 7 which forms the bottom of the chamber 9, 70 through the chamber 10 and into the upper part of the chamber 16, as illustrated.

Any suitable means may be employed for controlling the flow of water from the chamber 9 through the tube 17 and there is here 75 illustrated a needle valve 18 which is shifted by a suitable screw 19 under the control of a handle 20 which is positioned above the top of the receptacle 1, the screw 19 being threaded in a suitable sleeve in the top 80 of the receptacle.

A suitable spout 21 is provided to facilitate the introduction of water into the chamber 9.

Mounted upon suitable brackets such as 95 those indicated at 22 upon the top of the receptacle 1, is an electric motor 23, the armature shaft of which is vertically disposed and either extended to form the shaft 24 or having the shaft suitably coupled 100

thereto. This shaft 24 extends downwardly through suitable bearing sleeves, into the lather chamber 16 and upon its lower end is a key 25 which positions in a suitable key-way 26 in the wall of a tube 27 into which the shaft extends. This tube 27 is connected with the top of a circular brush 28, the bristles of which rest upon a cake of soap 29 in the bottom of the chamber 16 and resting upon the removable base for the receptacle. Means is thus provided whereby up and down movement of the brush is permitted relative to the shaft.

The cable 14 may be provided with a switch 30 at a point between the heating coil 12 and the motor so that the motor may be started or stopped without interfering with the operation of the heating coil.

In Figure 2 a slightly modified form of the invention is illustrated wherein the receptacle 31 constitutes the lather chamber and this is mounted upon a suitable base 32 and closed by a removable cap 33 at its lower end. The motor and brush structure for forming the lather and the draw-off faucet or spout and valve therefor are the same as shown and described in the preferred form.

Mounted upon the base 32 beside the receptacle 33 is a casing 34 which engages the receptacle 31 at one side and which has its bottom open as at 35 while its top is formed to provide a receptacle 36. The top of this receptacle has a filling opening 37 therein and a pipe line connects the bottom of the receptacle with the lather receptacle 31, as indicated at 38, which line is controlled by a suitable valve 39.

The water within the receptacle 36 is warmed and maintained in such condition by the use of an incandescent lamp 40 mounted in a suitable manner in the casing 34 beneath the water receptacle. The structure here shown for the support of the lamp 40 comprises a bracket 41 removably attached to the wall of the casing and carrying a socket 42 into which the base of the bulb is threaded.

From the foregoing it will be readily apparent that with the devices herein described a suitable heavy lather may be easily and quickly worked up in either of the lather receptacles by introducing a slight amount of water into the chamber containing the soap and then running the motor connected with the lather brush, for a suitable period of time. Upon opening the valve 5 the lather will flow from the receptacle into a suitable receiver from which it may be dipped for use. It will thus be apparent that the lather may be transmitted directly from the mixer to the face of the user, without the use of any brush or other applying implement, thus making it possible for barbers to comply with the law in certain sections which pro-

hibits the use of the same shaving brush by barbers for lathering the faces of different customers. The device, therefore, has advantages from a sanitary point of view as well as an economical one.

70

As one becomes accustomed to using the lather mixer it will be possible to judge the approximate amount of lather required for a shaving operation and thus no more than the required amount need to be drawn from the receptacle.

75

Having thus described the invention, what is claimed is:—

1. A lather mixer comprising a receptacle, a cover removably attached to an end of the receptacle, an outlet for the receptacle, a rotatable shaft disposed vertically in the receptacle and extending to the exterior thereof, a brush member having a sleeve, the brush being within the receptacle and having the sleeve slidably receiving an end of said shaft, means preventing turning of the sleeve on the shaft a liquid chamber having communication with the receptacle, means for warming the said chamber, and valve means for regulating the flow of liquid from the chamber into the receptacle.

80

2. A lather mixer comprising a receptacle having a removable bottom, an outlet for the receptacle, means to provide two chambers in the upper part of the receptacle, the uppermost one of said chambers being designed to contain a liquid, a heating element in the other of said chambers, means for conducting liquid from the liquid chamber into the lower part of the receptacle, means for controlling the flow of liquid into the receptacle, an electric motor mounted upon the top of the receptacle and having the armature shaft extending downwardly into the lower part thereof through said chambers, a brush within the lower part of the receptacle having a sleeve receiving the adjacent end of said shaft, means for slidably connecting the sleeve with the shaft, and means for preventing turning of the sleeve on the shaft.

85

3. A lather mixer, comprising a lather receptacle, a valved outlet for the same, means for forming a lather in the receptacle, a casing adjacent the receptacle formed in its upper part to provide a liquid chamber, a valved pipe connecting said liquid chamber with the receptacle, and heating means within the casing beneath said chamber.

90

In testimony whereof I hereunto affix my signature.

MELVIN ROLSTAD.
